PHOTOELECTRIC BURGLAR ALARM UNIT

Robert T. Aull, Levittown, and Edmund A. Gleason,
Jackson Heights, N.Y., assignors to American District
Telegraph Company, Jersey City, N.J., a corporation
of New Jersey

Continuation of design applications Ser. Nos. 55,425 and
55,426, Apr. 9, 1959. This application Apr. 11, 1960,
Ser. No. 60,261

Term of patent 14 years

(Cl. D72—1)

FIG. I.

FIG.2.

FIG.4.

FIG.3.

FIG. 5

FIG.6.

FIG. 8

FIG. 7.

Fig. 1 is a front perspective view of a photoelectric burglar alarm unit embodying our new design;

Fig. 2 is a front elevation thereof as shown in Fig. 1;

Fig. 3 is an elevation thereof as seen from the opposite side of Fig. 1;

Fig. 4 is a rear elevation thereof as shown in Fig. 1;

Fig. 5 is a front perspective view of a modified form of the photoelectric burglar alarm unit shown in Fig. 1;

Fig. 6 is a front elevation thereof as shown in Fig. 5;

Fig. 7 is an elevation thereof as seen from the opposite side of Fig. 5;

Fig. 8 is a rear elevation thereof as shown in Fig. 5.

This application is a continuation of our pending applications Serial Nos. D. 55,425 and D. 55,426, filed April 9, 1959, which applications are now abandoned.

We claim:

The ornamental design for photoelectric burglar alarm unit, as shown and described.
